UNITED STATES PATENT OFFICE.

DONALD McDONALD, OF LOUISVILLE, KENTUCKY.

JAIL-WINDOW.

SPECIFICATION forming part of Letters Patent No. 374,800, dated December 13, 1887.

Application filed October 11, 1887. Serial No. 252,095. (No model.)

To all whom it may concern:

Be it known that I, DONALD McDONALD, of Louisville, in the county of Jefferson and State of Kentucky, have invented a new and useful 5 Improvement in Jail-Windows, of which the following is a specification.

The invention relates to the windows of stone jails.

Heretofore such windows have been made 10 by standing large stones on end at intervals of about five inches, thus giving an opening large enough to admit light and air, but too small to allow the escape of prisoners. This construction is defective on account of the fact that 15 tools and other things could be handed in to the prisoners through such openings, and on account of the further fact that when one of the upright stones was pushed over against the other an opening was made large enough for a 20 man to pass through. Both of these objections I obviate as follows, reference being had to the accompanying drawings, on which similar letters of reference indicate like parts.

Figure 1 is an elevation of the jail-window 25 from the inside. Fig. 2 is an enlarged partial plan with the lintel E removed and the window-frame in section. Fig. 3 is a vertical section through one of the window-frames.

The slits or windows are made by standing 30 the stones A A on end and pinning them securely by dowel-pins *a* to the lintel E and the sill D. Before these stones are set, channels *c* are cut in them, thus forming a check, into which the flanges of frames F are slipped be-

fore the lintel E is set. The gratings B B are 35 made of strong wire or small iron bars closely woven into stout iron frames F.

It is obvious that as long as these gratings remain unbroken nothing larger than their meshes can be passed in through the windows, 40 and at the same time it is impossible to move one of the stones any nearer to the other, as the grating-frames prevent such motion.

S is a series of small metal sashes hung in the iron frame F, set in the openings, the wires 45 being set far enough to one side to allow room for the iron sash. The sashes are hung from the top, are connected together by a rod, *r*, and are operated by a string, *t*, reaching inside, so that they can be opened and closed by the 50 prisoners.

This device has the following advantages: First, the sash can be opened and closed by the prisoners; second, the glass is protected by the wire, so that the prisoners cannot break it. 55

What I claim is—

1. The combination of the gratings B with the grooved stones A, in the manner and for the purpose set forth above.
2. The combination, with the grooved stones A A and the gratings B set therein, of the hinged or swinging sash S, with connecting-rod *r* and operating-cord *t*, substantially as and for the purpose described.

DONALD McDONALD.
